UNITED STATES PATENT OFFICE.

WILLIAM WENDERHOLD, OF NEW YORK, N. Y., ASSIGNOR, BY MESNE ASSIGNMENTS,
TO CRU PATENTS CORPORATION, A CORPORATION OF NEW YORK.

ELECTRIC ARC LAMP.

Application filed January 14, 1918. Serial No. 211,842.

To all whom it may concern:

Be it known that I, WILLIAM WENDERHOLD, a citizen of the United States, residing at New York city, in the county and 5 State of New York, have invented certain new and useful Improvements in Electric Arc Lamps, of which the following is a clear, full, and exact description.

This invention relates to an improvement 10 in electric arc lamps, especially such as used in projection apparatus and the like.

The object of the invention is to provide a lamp with adjustment means that will make it possible to use the carbons in vertical and in a 90° angular position.

Another object is to make the apparatus quickly changeable from horizontally to a vertically operating lamp without change of its operating means.

20 Referring to the drawings—

Fig. 1 is a front elevation of the device.

Fig. 2 is a detail view, partly in section.

Fig. 3 is a rear elevation of my invention.

Fig. 4 is another view thereof.

25 Fig. 5 is a top view of the device.

As shown in the drawings, the central support 1 has a pivot bar 2, upon which pivot bar are mounted the carbon holder supports 3 and 4. The center of the pivot 30 2 is in alignment with the center point of the formation of the arc. The support 1 has a circular portion 1^x whose center is also common with the arc and pivot 2, which circular portion 1^x has slots 1^a and 1^b therein.

35 Screws 5 and 6 pass through these slots and are screwed into the carbon holder supports 3 and 4 (see Fig. 3). The carbon holder supports can be swung around the pivot point 2 into any desired position, and then 40 fastened by the screws 5 and 6, obviously both carbon holder supports could be provided with a worm gear and worm if desired.

To operate the carbon holder, I mount a gear 8 on the pivot bar 2, which gear meshes 45 with the gear 9 on the lead screw 10, and

with the gear 11 on the lead screw 12, and also meshes with the gear 13 on the driving bar 14, which bar may be operated by hand or power.

It is readily understood that no matter 50 what position the carbon holder supports are put, the operating means for the carbon feed remain intact.

While I have shown and described a specific structure embodying the principles of 55 my invention, I wish it to be understood that my invention in its broad scope as defined by the claims is not to be limited or restricted thereto, as many changes in details of construction will readily appear to those 60 skilled in the art without departing from the contemplated spirit and scope of my invention.

What I claim as my invention is:

1. In an arc lamp, a plurality of carbon 65 holder supports, means for pivotally mounting said supports for independent movement about a common axis, said axis being substantially in alignment with the arcing tips of the carbons.

2. In an arc lamp, a plurality of carbon 70 holder supports, means for pivotally mounting said supports for independent movement about a common axis, said axis being substantially in alignment with the arcing 75 tips of the carbons, and means for positioning said holder supports.

3. In an arc lamp, a plurality of carbon 80 holder supports, carbon holders thereon, means for pivotally mounting said supports for independent movement about a common axis, said axis being substantially in alignment with the arcing tips of the carbons, and means for moving said holders towards and away from said axis irrespective of the 85 pivotal position of said holders.

Signed at the city, county and State of New York this 9th day of January, one thousand nine hundred and eighteen.

WILLIAM WENDERHOLD.
